READING AND WRITING TABLE

Wilbert Blake Love, Mountain Lake Park, Md.

Application July 27, 1938, Serial No. 221,550

2 Claims. (Cl. 45—60)

This invention relates to a reading and writing table especially intended for use by invalids who are forced to lie in bed, but may be used by anyone desiring to read or write in a lying down or reclining position.

Many persons are either temporarily or permanently afflicted in such a way that they have the free use of their arms but are unable to be in any position other than a lying down position or a reclining position. Such persons find it very difficult to write letters or to read because of the necessity of continuously holding the paper or book in an inverted position above them. Especially in writing is this difficult because the paper must be supported on some rigid backing which also has to be held up. Persons afflicted in this way can write only to a very limited extent and their arms quickly tire in reading so that their enjoyment from this source is very limited. Invalids who cannot use their arms may have a reading material supported before them and an attendant may turn the pages.

The present invention provides a bedside table into which a single sheet of writing paper or a thick book, or a large magazine, or any other reading or writing material can be placed and rigidly held in any convenient position to be used by the invalid. The paper or book is held stationary and the patient can quickly adapt himself to writing almost as easily as if he were sitting upright with the paper on a desk below him in the normal way. The present invention further contemplates the use of holding means for retaining the book or paper in position which will accommodate itself to articles of different sizes and thicknesses, but the holding means is also of such a character that it will not obscure any part of the printed page and need not interfere with the area of the paper which is being used for writing.

The invention may be readily understood by reference to the accompanying drawings in which

Fig. 1 is a side elevation of a table embodying my invention illustrating how the same may be used by an invalid;

Fig. 2 is a plan view on a larger scale of the face of the table or tray which is turned toward the user;

Fig. 3 is a perspective view of the table and stand;

Fig. 4 is a detail view showing a portion of the table or tray on a substantially full sized scale and showing in detail the clamping means for holding the table at the angle to which it may be adjusted.

The table preferably comprises a tripod type of stand 2 having three legs 3 two of which may be placed parallel with the bed and the third of which may project under the bed so as to obstruct the space alongside the bed as little as possible. 5 The tripod carries an upright rigid tube 4. Into this tube there is telescoped a supporting member 5 which is also preferably of tubular construction, the upright 4 having a hand-screw 6 by means of which the support 5 may be adjustably 10 clamped at any desired vertical elevation. The support 5 carries a rigid horizontal arm 7. The tray or table designated generally as 8 is carried on this horizontal arm. It is supported in such manner that it may rotate about the arm as an 15 axis and be adjustably clamped in the position to which it is rotated.

The table or tray 8 comprises a smooth panel 9 of wood or other suitable material. Around this panel is an upstanding frame or ledge 10. At one 20 side of the table or tray 8 is a plate 11 having an opening therethrough of a size to fit about the horizontal arm 7 of the stand. Secured to the other side of the tray is a generally similar plate 12 having a smaller opening therethrough. The 25 end of the tubular arm 7 is provided with a cap 1a at its free outer end, and this cap abuts the inner face of the plate 12. Within the inner end of the arm 7 is an internally threaded bushing or nut 1b. The threaded stem 13 of a hand-wheel 14 passes through an opening in the plate 12 and threads into the bushing or nut 1b. By tightening up on the hand-wheel 14, the plate 12 will be frictionally clamped between shoulder 14a on the stem of the hand-wheel and the terminal 35 cap 1a on the arm 7. This is merely typical of one type of clamping adjustment that can be used for holding the table at different angles.

Secured to the frame 10, preferably at two sides and one end thereof, are paper and book holding 40 clips 15. These clips, which are preferably formed of relatively stiff flat spring metal are pivotally attached to the frame at one end. If the tray is made of wood, screws 16 may be used for securing the clips in place. The clips are 45 outwardly bowed to give them added resilience and they have free terminal portions which are rounded, these terminal portions being designated 15a. The clips are preferably arranged in pairs, the two clips of each pair being separated 50 several inches. The clips can be swung around to a position parallel with the frame and sprung upwardly to rest on the frame. For holding a book or paper of small size, they are swung out to the position shown in Fig. 2 where they are 55

perpendicular to the frame on which they are mounted. If they project over the printing in a book, for example, they can be swung to a proper angle so that the terminal portions will rest in only the margins of the book. It is not, of course, necessary that all of the clips be used at all times, the number of clips employed depending largely on what is being clipped against the face of the tray or what the operator finds convenient to use.

10 The tray is preferably of a dimension such that it may hold a large magazine, while the clips 15 are of sufficient length that they may swing in to hold an ordinary sheet of writing paper. In reading a book, for example, the pages may be easily pulled from under the clips and inserted under other clips, particularly where the clips are set to overhang only the margins of the book. In many cases the tray may be in a substantially vertical position in which the book will rest on one of the frame strips 10; i. e., the lowermost strip as shown in Fig. 2, and only the two lowermost clips are required to hold the pages from turning.

15 A suitable reading lamp 17 is attached to the ledge 10 of the tray as indicated in Figs. 1 and 3. The lamp is arranged so that the light rays therefrom shine on the tray but not in the eyes of the reclining person.

20 The stand for supporting the tray is preferably formed of relatively heavy tubular metal with the spread of the tripod being substantial so that the standard will not move in turning the pages of a book. While the table has its principal usefulness for invalids who have to be in a lying down or generally reclining position, it may

also be used by persons who desire to read in a semi-reclining position without holding the book. The tray can also be inverted to be used as a sick room table.

25 While I have specifically illustrated and described one particular embodiment of my invention, it will be understood that this is by way of illustration and that various changes and modifications may be made in the construction within the contemplation of my invention and under the 10 scope of the following claims.

I claim:

1. A reading and writing desk for reclining persons comprising a stand, a vertically adjustable support on the stand having a horizontal 15 arm thereon, a tray pivotally supported on said arm for rotation about the arm as an axis, said pivotal support including a plate extending from the tray at the free end of said arm, clamping means for clamping the plate to the end of the 20 arm for releasably holding the tray in any selected position to which it may be rotated, and means on the tray for holding books and papers against the tray when the tray is inverted.

2. A reading and writing table for use by reclining persons comprising a tray having a panel and a frame surrounding the panel, resilient sheet metal spring clips pivotally secured to the frame and arranged to be projected over the panel and also to be moved into a position over the frame 30 clear of the panel, means supporting the tray in an upside down position, said clips being arranged along two sides and one end of the tray in spaced pairs.
